UNITED STATES PATENT OFFICE.

GEORGE L. DAVENPORT, JR., OF LOS ANGELES, CALIFORNIA.

RADIANT-HEATER ATTACHMENT.

Application filed August 1, 1927. Serial No. 209,832.

My invention relates to radiant electric or gas heaters for domestic use, and it has for a purpose the provision of an attachment for heaters of this character by which the 5 radiant heat generated therein is converted into convected heat by causing air to be circulated by thermal action through the interior and against the exterior of the attachment, thus heating the air more rapidly and 10 thereby increasing the heating efficiency of the conventional radiant heater.

I will describe only one form of radiant heater attachment embodying my invention and will then point out the novel features in 15 claims.

In the accompanying drawing:

Fig. 1 is a view showing in side elevation one form of attachment embodying my invention in applied position to an electric radiant heater; 20

Fig. 2 is a view showing the heater and attachment in top plan; and

Fig. 3 is a vertical sectional view taken on the line 3—3 of Fig. 1.

In carrying out my invention, the attachment may be of any suitable design to render it applicable to a gas or radiant heater of any particular form so long as it embodies the structural characteristics necessary to 25 accomplish the conversion of radiant heat into convected heat.

My invention in its present embodiment is in the form of a cylindrical body 15 of metal or other suitable material and of such diameter as to render it applicable to the concave side of a reflector of an electrical radiant heater. One end of the body 15 is closed by a wall 16, the opposite end of the body being open and detachably secured to the reflector 40 R of the heater by means of clips 17 arranged at circumferentially spaced intervals on the attachment body so as to engage the periphery of the reflector and thereby secure the attachment to the reflector in such position that its axis is centered with respect to 45 the axis of the reflector.

As clearly illustrated in Fig. 3, the inner side of the wall 16 is provided with a suitable baffle member 18 which, in the present 50 instance, is cylindrical in form and positioned concentrically of the body 15 so as to provide an interposing medium between a pair of openings 19 and 20 formed in the body 15 preferably at diametrically opposed 55 points. In the present instance the lower opening 19 is disposed directly below the

baffle member 18, and the upper opening 20 directly above the baffle member. The lower opening constitutes an inlet for air, and the upper opening a discharge through which the 60 heated air can escape from the attachment.

In practice, the radiant heat emanating from the heating unit H of the electric heater is projected forwardly by reason of the reflector R, and with the attachment applied as 65 illustrated, it will be manifest that the attachment body including the baffle 18 intercepts a maximum quantity of the heat rays so that the attachment becomes heated interiorly and exteriorly. By reason of the 70 openings 19 and 20 the thermal action of the radiant heat causes atmospheric air to be circulated through the interior and against the exterior of the attachment whereby a more rapid heating of the air is effected than 75 is possible by direct radiation. Thus, the heating efficiency of the heater is greatly increased.

By a consideration of Fig. 3 it will be evident that the baffle 18 distributes the incoming cool air uniformly over the entire interior surface of the attachment thereby effecting a maximum conversion of the radiant heat into convected heat, the heated air escaping through the opening 20 to atmosphere. 80 In this manner a constant circulation of cool air interiorly of the attachment is produced, and conversely a consistent discharge of heated air from the attachment.

My invention renders more practicable the 90 use of a radiant heater in a small room, such as a bathroom, where concentrated reflected heat is impractical and dangerous. In actual use my attachment provides a heating surface of relatively low temperature due to 95 the constantly circulating convection currents, the temperature being similar to that of a steam radiator and thereby reducing fire risk and preventing "burning" or overheating of the air which results by direct 100 contact with highly heated surfaces, and which is objectionable from a sanitary and health standpoint.

Although I have herein shown and described only one form of radiant heater attachment embodying my invention, it is to be understood that various changes and modifications may be made herein without departing from the spirit of the invention and the 105 spirit and scope of the appended claims.

I claim:

1. An attachment for radiant heaters com-

prising a circular body closed at one end and open at the other, diametrically opposed openings in the body adjacent the closed end thereof, and a circular baffle in the body and concentrically spaced therefrom, said baffle being disposed between said openings.

2. The combination with a radiant heater employing a concavo-convex reflector, of an attachment therefor consisting of a cylindrical body member open at its rear portion and closed at its front portion, the open rear portion having a diameter agreeing approximately with that of the reflector of the heater,

a cylindrical baffle extending from the closed front portion of the body member and terminating in spaced relation to the said open rear portion and being of less diameter than the inside diameter of the body member, the body member having an air intake opening at a point beneath the baffle and an outlet opening above the baffle for the heated air, and means securing the body member to the reflector of the heater so as to closely relate the said open rear portion with the concave of the reflector.

GEORGE L. DAVENPORT, JR.
